(57) **CLAIM**

The ornamental design for a fluid pressure cylinder, as shown and described.

DESCRIPTION

FIG. 1 is a front view of a fluid pressure cylinder showing our new design;

FIG. 2 is a rear view of the fluid pressure cylinder;

FIG. 3 is a top view of the fluid pressure cylinder;

FIG. 4 is a bottom view of the fluid pressure cylinder;

FIG. 5 is a right side view of the fluid pressure cylinder;

FIG. 6 is a left side view of the fluid pressure cylinder;

FIG. 7 is an enlarged cross-sectional view of the fluid pressure cylinder taken along line 7—7 of FIG. 1; and,

FIG. 8 is a perspective view of the fluid pressure cylinder.
